PRESSING MACHINE

Charles Mendelson, New Rochelle, N. Y.

Application April 9, 1938, Serial No. 201,143

9 Claims. (Cl. 223—57)

The invention relates to pressing machines used to press or iron goods such as shirts and other garments, small flat work, etc., and more particularly to that type of machine wherein the garments or the like are subjected to pressure between heated members, one at least of which embodies a more or less resilient pad.

It has been the practice heretofore, more especially in the ironing of shirts and the like, to iron the shirt bosom and then to finish the sides and back in another operation or operations.

It is an object of the present invention to provide ironing mechanism whereby a finish of the entire shirt, other than its cuffs, sleeves, and collar band, may be effected in a single operation.

A further object of the invention is to provide a machine of this character which may readily be adapted to the ironing also of other articles of apparel or to flat work and serving as a body press.

In carrying out the invention, there is provided upon a suitable supporting member or standard a stationary intermediate buck composed of separable halves, the one surface of the buck being of suitable shape for the work to be ironed or pressed and designed to cooperate with a movable platen which will press and hold a portion of the article to be finished, while its opposite and separable surface is designed to engage and distend or tension a further portion or portions of the article. The said buck is free at one end to admit of placing readily thereover the work to be ironed; and a collar or collar band retaining element is associated with said buck at the free end and comprises a holding portion which is entirely independent of an abutment portion separably secured to the buck, so that it may be removed if it be desired to utilize the buck for the pressing of articles not requiring a collar or collar band hold.

In the case of the pressing of a shirt with tail, provision is made for a movable element to engage this depending portion to effect also a finish thereon.

The nature of the invention, however, will best be understood when described in connection with the accompanying drawings, in which:

Fig. 1 is a transverse section through the novel pressing machine.

Fig. 2 is a fragmentary longitudinal section taken on the line 2—2, Fig. 1 of the drawings, and looking in the direction of the arrows.

Fig. 3 is a horizontal section taken on the line 3—3, Fig. 1 of the drawings, and looking in the direction of the arrows.

Fig. 4 is a fragmentary side elevation.

Fig. 5 is a fragmentary front elevation, to an enlarged scale, illustrating the collar band holding means; and Fig. 6 is a transverse section through one portion thereof.

Fig. 7 is a perspective view, and Fig. 8 a transverse section taken on the line 8—8, Fig. 7, of a camming element forming part of the operating mechanism for said holding means portion.

Fig. 9 is a fragmentary longitudinal section 10 illustrating a modification of the pressing machine.

Fig. 10 is a fragmentary transverse section 15 illustrating a further modification of the pressing machine.

Referring to the drawings, 20 designates the base of a suitable supporting frame having the standard or upright member 21 which carries a pivoted pedal 22 or other known means for operating a platen 23. This platen is hollow so that it may be heated, as through a steam admission pipe 24; and it is pivotally carried at the top of the standard through a lever 25 which in turn is connected to the pedal 22 by a link 26.

The said platen 23, moreover, is normally held 25 in the elevated position, shown in Fig. 1, as by means of a spring 27, one end of which is attached to the standard and the other to the link arm of the lever 26. It is designed to be depressed in the usual manner through pedal 22 30 for contact with the upper surface of a stationary buck mounted upon a further and hollow standard 30 secured to the base.

The buck, as shown, comprises an upper half 31, which is provided with an ironing or pressing pad 32, and a lower half 33. Both of the halves are provided with heating ducts 34 and 35, respectively, to which steam may be introduced, in the case of the former half through the pipe connection 36 and in the case of the latter half 40 through a flexible connection 37. The latter half, in accordance with the invention, is made separable from the upper and fixed half; and the upright 38 to this end is provided with a horizontally directed channel portion 40 to which 45 the upper half is fixedly secured as by a screw 41, while the lower half is normally held thereto through the action of a pair of springs 42 which are attached at their opposite ends respectively to said lower half and to the horizontal channel 50 portion 40, as shown.

To separate the said lower half 33 from its fixed upper half 31, the channel portion 40 carries also a pair of cylinders 43 with pistons having projecting piston rods 44 extending down- 55

wardly to engage bosses 45 upon the inner surface of the lower half of the buck. The latter is hollowed to accommodate the cylinders and springs, as well as the pipe connections 46 for introducing 5 a fluid actuating medium to the said cylinders.

The connection for the fluid, which may be air under suitable pressure, communicates with a suitable source of supply as indicated at 47, there being included an intermediate pressure 10 regulator or check-valve 48 whereby the pressure to be applied to the pistons for advancing their piston rods 44 will be limited and will thus determine the extent of separation of the lower half from the upper half in overcoming the force 15 exerted by springs 42. A definite limit to this extension of the lower half or expansion of the buck is provided through pairs of angle brackets 50 which extend upwardly from the inner surface of the lower half outside of the channel portion 20 40, and carry horizontally disposed rollers 51 projecting into vertically disposed grooves 52 in the outer surfaces of the walls of the channel portion. Suitable stops 53 at the bottom of the respective grooves limit the travel of the rollers 25 55 and thus of the said lower half. A peripheral shield 54 attached to the fixed half and extending over the lower half serves to conceal the interior of the buck when its halves are thus separated.

30 On top of the upper half of the buck there is provided the usual collar or collar band abutment or form 55 when the apparatus is to be utilized for the ironing of a shirt. This abutment, however, is removably attached, as by means of the 35 thumb screw 56, to the end of the upper half so that the apparatus may be used interchangeably as a shirt press or a body press or as a family press wherein it is unnecessary to expand the buck. This end, furthermore, as well as the associated lower half, is perfectly free and not connected to other portions of the frame so that goods may be freely placed over the buck which, in the case of a shirt would be the bosom, to be located on the padding 32; and when the platen 40 45 23 is then depressed to contact this portion of a shirt, it will be firmly held to the padding.

Thereupon, the lower half may be separated to distend or tension the rest of the body portion of the shirt so that this will also receive a finish 50 through contact with the outer surface of the said lower half. In operating the press in this manner, it will be understood that the platen is first depressed by stepping upon the pedal 22 whereupon the fluid pressure is supplied as by 55 turning the handle 49 to afford communication from the source 47 through the pressure-regulating means 48 to the pipe connection 46, and the respective cylinders 44.

In view of the free-ended buck member utilized 60 with the novel pressing machine, the collar holder or clamp, when working with shirts and the like, is mounted independently of said buck as upon a further upright or standard 60. As shown in the drawings, more particularly Figs. 65 5-8, the holder comprises a U-shaped support 61 carrying the holding loop or yoke 62 designed to contact with the abutment 55 in holding a collar band in position on the buck, said member being urged in a direction toward the buck by means of a spring 63 attached to the standard 60 and bearing 70 against the said U-shaped member. This member is pivotally mounted on the standard 60 to maintain normally an upright position, having to this end a rod 64 passing through and fixed 75 to a body portion of the support 61 which is

mounted to ride in slots 65 of a U-shape inclined bracket 66 fixed to the upright while its respective ends enter slots 67 in oppositely disposed arms 68 and 68' of the actuating lever. The latter is mounted in the standard to rock about 5 the pivot shaft 69.

To insure a normal upright position of yoke 62, a pair of cam elements 70 formed on the bracket at one end of its slots 65 cooperates with fingers 71 on the rod 64. When the actuating 10 lever 68 is angularly moved (to the left in Fig. 5) rod 64 moves downwardly in slots 65, allowing yoke 62 to turn under the influence of spring 63 to the position indicated in broken lines, Fig. 5. A pair of clips 72 located at the respective sides 15 of the bracket at the lower end of the slots serve to lock the rod 64 in this position. To release the yoke, the action is the reverse, fingers 71 engaging the cams and elevating the yoke to the position shown in full lines. 20

By turning the handle 68 so that the loop 62 moves in the direction indicated by the arrow, the said loop 62 will be brought over abutment 55 to the position indicated by the broken lines to clamp the collar band or collar thereto during 25 the pressing operation. Upon completion of this operation, handle 49 will be returned to normal position, as shown in the full lines, to restore the lower half to its normal position in contact with the upper half, whereupon the platen may be 30 released by foot pressure on a release pedal 75 having the spring-drawn detent 76 for locking the pedal 22 in its depressed position upon lowering the platen to the buck.

In the ironing of shirts, with tail portions, it is, 35 of course, desirable that such portions also be finished; but as such portions will depend from the body portion proper, no contact will be had with the under surface of the separable halves of the buck when this is depressed as hereinbefore 40 set forth to tension the rest of the body portion of the work. There is provided, to this end, a finishing element located below the buck and associated preferably with a tray portion 80 which is also located beneath the buck and fixedly 45 mounted upon the said standard 21, said tray serving to catch any work which might slip from an operator's hand. The said finishing element is designed to receive simultaneously a movement longitudinally of the buck and toward the same 50 so as to pick up the depending shirt portion and carry it into contact with the outer surface of the said lower half and provide a finish thereon. This action is timed to occur, however, after the lower half has been expanded, the movement of 55 the said element being therefore retarded with respect to the movement of said lower half.

This is conveniently effected by making the pipe connection 82 for the actuating fluid for 60 said element of lesser cross-sectional area than the connection 46 for actuating the piston rods 44, both connections being made to the common source 47 and beyond the pressure regulator 48. Therefore, when the handle 49 is manually actuated to supply the fluid pressure, while both the 65 buck half and the said element begin to move, the half will reach its limit of extension before contact is made with said half by the said element.

As indicated, this element is channel-shaped 70 and comprises a U-shaped member embodying the sides 85 designed to embrace the side walls of the lower half 33 of the buck and a bottom 86 shaped to conform to an enlargement 87 of the under surface of said half for pressing ma-

terial therebetween. It is mounted, also, to rock upon a support 88 and is resiliently positioned thereon by leaf springs 89 and 90 located upon opposite sides of its pivot 91. The support or platform 88 in turn is carried by pairs of links 92 pivoted also to the standard 30 to which is also pivoted an operating cylinder 93 in communication with the source of fluid supply through the pipe connection 82. A piston 94 movable in this cylinder under the action of the fluid supply is pivotally connected to one of the pairs of links through a connecting cross-rod 95, and the said pair of links are also normally urged by a spring 96 to the position shown in Fig. 2 of the drawings, wherein the channel element is shown as located in its lowermost position. A nose 97 extending from the cylinder 93 is provided to engage the standard 30 for limiting the movements of the cylinder, links and channel element. When pressure is applied to piston 94, the channel element will be elevated and at the same time moved longitudinally of the buck half due to the linkage connection shown; and it will thus gradually pick up a depending portion of the work to carry it into contact with the under surface of the lower half of the buck.

In Fig. 9, a modification is indicated, more especially in relation to the movable element which is indicated therein as being combined with the tray portion. Thus, below the intermediate buck with its upper fixed half 100 and its lower separable half 101, there is located a tray member 102 having the shaped end portion 103 adapted for engagement with the depending portion of the work, as in the previously described embodiment. The remainder of the bottom of the said tray in this embodiment engages also the entire back and part of the sides of work mounted over the buck. The combined tray and finishing element is resiliently supported upon a table 104 through springs 105 and 106, and is projected toward and longitudinally of the buck by a piston 107 operating in a cylinder 108, as hereinbefore set forth. This type of the apparatus is particularly suitable for use as a light coat, smock or jacket press. Both the platen and tray may be suitably lined, if required.

Fig. 10 shows a further modification wherein the combined tray and finishing element 110 has combined therewith a heating chamber 111 as for steam which may be introduced therein through a flexible connection 112. The said combined element which is designed, as in the previous embodiment, to be advanced toward and longitudinally of the buck member as the lower half 113 of the latter, is padded in this embodiment and extended from its upper half 114 after the platen 115 has secured the work to the pad 116 of said upper half. By this expedient, and in view also of the free end of the buck, particularly when the abutment is removed, heavy pressing may be accomplished thereon, as of woolen overcoats and the like.

I claim:

1. In a pressing machine: a frame, an intermediate ironing buck supported thereon and including a fixed padded half and a separable movable half, together with means to heat both of the halves, a platen adapted for engagement with the fixed half of the buck to press work thereon and hold a portion thereto, together with means to effect movement of the platen, means to effect the separation of the lower half of the buck from the upper half to tension a further portion of the work, an element located beneath

the buck, and means to position the said element against the lower half of said buck for engagement with a depending portion of the work.

2. In a pressing machine: a frame, an intermediate ironing buck supported thereon and including a fixed padded half and a separable movable half, together with means to heat both of the halves, a platen adapted for engagement with the fixed half of the buck to press work thereon and hold a portion thereto, together with means to effect movement of the platen, means to effect the separation of the lower half of the buck from the upper half to tension a further portion of the work, an element located beneath the buck, and means operative subsequent to the separation of the buck halves to position the said element against the lower half of said buck for engagement with a depending portion of the work.

3. In a pressing machine: a frame, an intermediate ironing buck supported thereon and including a fixed padded half and a separable movable half, together with means to heat both of the halves, a platen adapted for engagement with the fixed half of the buck to press work thereon and hold a portion thereto, together with means to effect movement of the platen, means to effect the separation of the lower half of the buck from the upper half to tension a further portion of the work, an element rockably and yieldably mounted beneath the buck, and means to position the said element against the lower half of said buck for engagement with a depending portion of the work.

4. In a pressing machine: a frame, an intermediate ironing buck supported thereon and including a fixed padded half and a separable movable half, together with means to heat both of the halves, a platen adapted for engagement with the fixed half of the buck to press work thereon and hold a portion thereto, together with means to effect movement of the platen, an element located beneath the buck, and movable into position against the lower half of said buck for engagement with a depending portion of the work and subsequent to separation of the said lower half from the upper half, pneumatic means for effecting the separation of the lower half of the buck from the upper half, pneumatic means for positioning the said movable element, and a source of air under pressure connected to the respective pneumatic means, the passage of air from said source to the positioning means for the movable element being retarded relatively to that for the buck separation means.

5. In a pressing machine: a frame, an intermediate ironing buck supported thereon and including a fixed padded half and a separable movable half, together with means to heat both of the halves, a platen adapted for engagement with the fixed half of the buck to press work thereon and hold a portion thereto, together with means to effect movement of the platen, an element located beneath the buck, and movable into position against the lower half of said buck for engagement with a depending portion of the work and subsequent to separation of the said lower half from the upper half, pneumatic means for effecting the separation of the lower half of the buck from the upper half, pneumatic means for positioning the said movable element, and a source of air under pressure connected to the respective pneumatic means, the cross-sectional area of the connection to the first-named pneu-

65

70

75

matic means being substantially larger than that to the last-named means.

6. In a pressing machine: a frame, an intermediate ironing buck supported thereon and including a fixed padded half and a separable movable half, a platen adapted for engagement with the fixed half of the buck to press work thereon and hold a portion thereto, together with means to effect movement of the platen, means to effect the separation of the lower half of the buck from the upper half to tension a further portion of the work, a tray located beneath the buck, and a movable element associated therewith, together with means to impart simultaneously to the movable element a movement toward and longitudinally of the lower half of the buck to cause said element to engage therewith when said lower half is separated from its upper half.
7. In a pressing machine: a frame, an intermediate ironing buck supported thereon and including a fixed padded half and a separable movable half, a platen adapted for engagement with the fixed half of the buck to press work thereon and hold a portion thereto, together with means to effect movement of the platen, means to effect the separation of the lower half of the buck from the upper half to tension a further portion of the work, a tray located beneath the buck, a movable element associated therewith, together with a fluid pressure cylinder pivotally attached to the frame and a piston extending therefrom, and link mechanism pivotally attached to the

frame and connected with said piston and the movable element to impart simultaneously to the latter a movement toward and longitudinally of the lower half of the buck to cause said element to engage therewith when said lower half is separated from its upper half.

8. In a pressing machine: a frame, an intermediate ironing buck supported thereon and including a fixed, padded half and a separable movable half, a platen adapted for engagement with the fixed half of the buck to press work thereon and hold a portion thereto, means to effect the separation of the lower half of the buck from the upper half to tension a further portion of the work, together with a pressing element located beneath the said separable half of the buck, and means to position the same against said separated half.

9. In a pressing machine: a frame, an intermediate ironing buck supported thereon and including a fixed, padded half and a separable movable half, a platen adapted for engagement with the fixed half of the buck to press work thereon and hold a portion thereto, means to effect the separation of the lower half of the buck from the upper half to tension a further portion of the work, together with a pressing element located beneath the said separable half of the buck, and means to position the same against said separated half with a movement longitudinally thereof.

CHARLES MENDELSON.
